UNITED STATES PATENT OFFICE.

HELENE L. SWEENEY, OF BOSTON, MASSACHUSETTS.

PORTIÈRE-HOLDER.

1,229,672.

Specification of Letters Patent.

Patented June 12, 1917.

Continuation of application Serial No. 130,257, filed November 8, 1916. This application filed May 14, 1917.
Serial No. 163,848.

To all whom it may concern:

Be it known that I, HELENE L. SWEENEY, a citizen of the United States, residing at Boston, county of Suffolk, State of Massachusetts, have invented an Improvement in Portière-Holders, of which the following description in connection with the accompanying drawing is a specification, like characters on the drawing representing like parts.

10 This invention relates to a device for application to a portière, curtain or similar article presenting a hook by which the portière, curtain or other article may be suspended from a suitable support such as the 15 usual curtain rings upon a curtain rod.

The object of the invention is to provide a device which is self-attachable to the portière, curtain or other article and which therefore requires no sewing or fastening to 20 hold it in place.

The object of the invention is to provide a device of this character with the hook portion alone of which shall be visible at the upper edge of the portière.

25 The object of the invention is to provide a device of this character in which the body or frame of the device shall be inserted within the upper folded edge of the portière and shall lie concealed in the fold.

30 The object of the invention is to provide a device of this character with an extended straight upper edge upon which the fold of the portière rests and with a pointed hook readily insertable through the material of 35 the portière. These and other objects of the invention will appear more fully from the accompanying description and drawings and will be particularly pointed out in the claims.

40 The drawings show the invention in its preferred forms for supporting a portière on an ordinary rod provided with curtain rings.

In the drawings,

45 Figure 1 is a perspective showing a curtain rod, rings and portière suspended therefrom by the aid of the device embodying this invention;

Fig. 2 illustrates a form of the invention 50 in place in the portière, a portion of the portière being shown and one fold being cut away at the medial line of the fold;

Fig. 3 is a side elevation of the device shown in Fig. 2;

Fig. 4 is a perspective view of the device 55 shown in Figs. 2 and 3;

Fig. 5 is a perspective view of another form of the device;

Fig. 6 is a perspective view of a third form of the device. 60

The device as shown in Figs. 2, 3 and 4 is formed from a suitable piece of wire, the size and flexibility of which is determined by the weight of the portière, curtain or article to be supported. It should be of sufficient strength to maintain its shape under ordinary conditions of use and of sufficient flexibility to enable it to be bent into the required shape. 65

The device presents as its body portion a 70 thin flat frame with an extended upper straight edge 1, adapted to lie within the folded edge of the portière. A hook 2 up-stands from the central portion of the straight edge 1 and is of just sufficient size 75 to pass through and project above the folded edge of the material 3 of the portière and enable it to engage the device by which it is supported as, for example, the usual eye 4 on a usual curtain ring 5. This hook at its 80 free end is bent slightly outward as shown at 6 and is sharpened to a dull point so that it may readily penetrate the goods of which the article to be supported is formed and without tearing or injuring the goods. 85

In the form of the invention illustrated the device is formed of a single piece of wire. This wire is bent to present a thin flat skeleton frame portion having the extended straight upper edge 1, the rounded ends 7 90 and the lower edge 8, all the parts lying in the same plane. Each end of the wire forming the frame is bent back toward the center and in this form of the invention the bent back portions form the extended straight 95 upper edge 1. Where the ends of the wire intersect they are twisted together as shown at 9, and one end after being thus twisted is extended upwardly and bent into the form of the upstanding hook 2 which preferably projects in a plane at right angles to the plane of the skeleton frame portion. Thus the device is very simply and inexpensively made of a single piece of wire. 100

Another form of the invention is illus- 105 trated in Fig. 5. In this case the extended upper straight portion 10 of the thin flat skeleton frame portion is continuous and

the ends of the wire are bent back toward the center of the frame and in the plane thereof to form the lower edge of the frame. These ends are then twisted together at 11, 5 one end preferably being also twisted about the upper edge 10 and extending upwardly and bent into the form of the upstanding hook 2 as before.

A third form of the invention is illustrated in Fig. 6. In this case the extended upper straight portion 12 of the thin flat skeleton frame portion rests at the middle upon one extreme end 13 of the wire. This end 13 with the other end of said wire are 15 each bent back toward the center of the frame and in the plane thereof to form the lower edge of the frame and then the ends are twisted together as illustrated to bring the extreme end 13 directly under the upper 20 edge portion 12 and then one end is extended upwardly and bent into the form of the upstanding hook 2 as before.

The manner of use of the device will now be apparent. When the portière as at 14 in 25 Fig. 1 has one end folded over as at 15 the hook 2 is inserted from the inside through the folded edge and drawn through until the extended straight portion of the thin flat skeleton frame lies against the inside of the 30 folded edge while the thin flat frame of the device lies flat between the two layers of the portière. Thus the entire device is concealed from view with the exception of the hook alone which projects above the portière 35 and is readily insertible in the device by which it is supported. It is unnecessary to attach the device by sewing or otherwise to the portière. As many of them are used as are necessary and as required by the article 40 to be supported.

If full length of portière is desired the

portion 15 of the portière may be a simple narrow turned over edge or hem and after the holders of this invention are placed in position may be sewed down to the main 45 layer of the portière in the usual manner.

This application is a continuation of my prior application No. 130,257 filed November 8, 1916.

Having fully described my invention, 50 what I claim as new and desire to secure by Letters Patent is:

1. A portière holder formed from a single piece of wire bent to present a thin flat skeleton frame portion having an extended 55 straight upper edge, each end of said wire bent back toward the center of said frame and in the plane thereof, the said ends being twisted together and one end projecting above the straight upper edge in the form of 60 an upstanding hook adapted to penetrate, and project above, the folded edge of the portière, with the frame portion lying within the folded edge of, and supporting, the portière. 65

2. A portière holder presenting a thin flat frame portion with an extended straight upper edge to lie within the folded edge of, and support, the portière, and a hook upstanding from the central portion of said 70 edge adapted to penetrate and project above the folded edge.

3. A portière holder presenting a thin flat skeleton frame portion with curved ends and an extended straight upper edge to lie within 75 the folded edge of, and support, the portière, and a hook upstanding from the central portion of said edge adapted to penetrate and project above the folded edge.

In testimony whereof, I have signed my 80 name to this specification.

HELENE L. SWENEY.
